UNITED STATES PATENT OFFICE.

ALPHONSUS L. GOLDEN, OF OAKLAND, CALIFORNIA, ASSIGNOR TO NATIONAL RADIO COMPANY, OF SAN FRANCISCO, CALIFORNIA, A CORPORATION OF ARIZONA.

OSCILLATOR.

Application filed September 16, 1919. Serial No. 324,153.

To all whom it may concern:

Be it known that I, ALPHONSUS L. GOLDEN, a citizen of the United States, residing at Oakland, in the county of Alameda and State of California, have invented new and useful Improvements in Oscillators, of which the following is a specification.

This invention relates to an oscillator for the production of high frequency oscillating currents for use in connection with radio telephones, telegraphs, and the like.

One of the objects of the present invention is to provide a simple, compact, easily operated and adjusted oscillator for use in connection with apparatus producing high frequency oscillating currents, said apparatus being greatly reduced in size and weight and design to employ only one pair of electrodes to produce the same amount of smooth, uniform, high frequency oscillations formerly produced by oscillators employing several pairs of electrodes.

Other objects of the invention will be as follows:

To employ metal electrodes submerged in distilled water, or a liquid which is not inflammable or explosive in any way, which will not produce objectionable fumes nor deteriorate with use, as is the case where alcohol is employed.

Employing a spark gap where electrodes are very close together to allow the condenser discharges to pass between the electrodes without creating too much heat, or, in other words, wasting energy in the form of heat in the surrounding liquid as well as in the electrodes.

To employ tubular electrodes which permit the vapor or gases formed to freely discharge, and furthermore, to provide novel means for circulating the distilled water through and between the electrodes to further facilitate cooling and instant removal of gases generated.

To connect the oscillator in such a manner that it may be either used in connection with a radio telephone or telegraph.

Further objects will hereinafter appear.

The invention consists of the parts and the construction, combination and arrangement of parts as hereinafter more fully described and claimed, having reference to the accompanying drawings, in which—

Fig. 1 is a diagrammatic view showing

the different apparatus employed in a wireless telephone and telegraph system.

Fig. 2 is a central vertical section through the oscillator.

Referring to the drawings in detail and particularly Fig. 1, I have shown the connection of the oscillator forming the subject matter of the present invention with the several other apparatus required in a wireless telephone or telegraph sending station, in which A indicates a direct current generator connected in series with a pair of electrodes indicated at B and C. Mounted in one side of said circuit is a main switch 2, a rheostat 3, and a choke coil 4, and mounted in the opposite side of the circuit is a choke coil 5. This part of the station completes the direct current supply circuit while the primary oscillator circuit passes through a condenser 6 which is connected in series with a primary coil 7 of a high frequency transformer connected across the terminals of the electrodes B and C forming the spark gap of the oscillator. The primary oscillator circuit is here shown in heavy lines to distinguish it from the current supply circuit. The secondary oscillator circuit consists of the secondary coil of the transformer, as shown at 8 and antennæ 9 and a transmitter 10, which is connected, as shown at 11, with the ground; the transmitter 10 being bridged by a switch 12 when the station is used for telegraph work and being open when used for radial telephonic conversation.

The several apparatus employed and the specific connections made do not form any important feature of the present invention as these may be changed to suit varying conditions and requirements and as the construction of the oscillator is the most important feature of the present invention, it will be readily seen that the circuit connections are only of minor importance and are merely shown to illustrate one of the uses of the oscillator.

The oscillator proper consists of a cylindrical container 14 provided with a cover 15, preferably constructed of insulating material. Mounted on top of the cover is a stationary core magnet 16 of suitable construction. Extending through the magnet is an adjustable core screw 17. Suspended from the cover are a pair of rods 17^a, which

are connected at intervals by cross bars 18, 19 and 20. The lower cross bar is provided for the support of the electrode B while the upper cross bars 18 and 19 serve as a 5 guide for a rod 21, on the upper end of which is secured an armature 22 and on the lower end the electrode C. The rod 21 is mounted in direct alignment with the screw core 17 of the magnet 16 and as the armature 10 is mounted on the upper end of the rod in close proximity to the lower end of the magnet core, it can readily be seen that the rod and electrode carried thereby will be attracted and lifted by the magnet whenever this is energized.

By referring to Fig. 2, it will be seen that the electrodes forming the spark gap are tubular in construction and that the lower electrode B is supported by a hollow 20 base member 23 which is connected with an elevated storage tank 24 by means of a pipe 25. Mounted on the pipe, outside of the tank 14 enclosing the electrodes, is a valve 26. This valve is opened and closed by 25 means of a magnet 27, as will hereinafter be described. The tank 24 is connected with the discharge side of a pump 28 of suitable construction and the suction side of the pump is connected by means of a pipe 29 30 with an overflow opening 30 formed in the tank 14.

In actual practice, I preferably employ electrodes constructed of tungsten metal and I also employ distilled water as a circulating medium. The tank 24 is provided for the reception of distilled water and the pump 28 for the circulation thereof. That is, the distilled water flows to the electrodes B and C by gravity but as it overflows from 35 tank 14 through the opening 30, it is returned and delivered to the tank 24 by means of the pump 28. The electro-magnets which cause the raising and releasing of the upper electrode and the opening and closing of the valve 26 are connected in 40 series by means of wires 30, 31 and 32, through a telegraph key 33 with contacts on the rheostat 3, as shown, which allows a by-path for the current entering the oscillator to pass through said electro-magnets upon the pressing of the key 33. When 45 the key is released the upper electrode C drops and upon striking the lower electrode destroys the spark gap produced by the separation of the electrodes and thereby 50 the creation of succeeding oscillations until the key is again pressed.

The pump 28 is driven by an electric motor 35. This motor is connected with 55 the oscillating circuit in practically the same manner as the electro-magnets 16 and 27, the current for the operation of the motor being obtained by bridging a portion of the rheostat by means of the wires 36 and 37.

When the generator circuit switch 2 is closed, the current will flow through the rheostat and the pump motor by-path to the choke coil 4; then through the connected electrodes to the return choke coil 5, back 70 to the generator. Upon depressing the key 8, the electro-magnets 16 and 27 become energized, thereby causing the valve to open and the upper electrode of the oscillator to be raised the proper distance for 75 the production of the spark gap, thus producing oscillations through the high frequency circuit. Water is at the same time admitted, due to the opening of the valve, and as the electrodes are tubular and hollow, 80 as shown, it can readily be seen that the water entering through tube 25 and the hollow base 23, will pass upwardly through the electrodes and out through a discharge opening 40, finally overflowing through the outlet 30, from where it is returned by means of the pipe 29 and pump 28 to the tank 24. A portion of the water admitted by the pipe 25 is also permitted to escape between 85 the faces of the electrodes and it is therefore 90 obvious that any gases or steam produced will be instantly liberated, either through the center of the electrodes or exterior of the same. The circulation of distilled water therefore insures cooling of the electrodes as 95 well as instant removal of any vapor formed by the spark discharged between the faces of the electrodes, thereby permitting the production of smooth, uniform, high frequency oscillations formerly only produced 100 by oscillators employing several pairs of electrodes.

Electrodes constructed of tungsten metal burn away very slowly. Comparatively little adjustment is therefore required and 105 as this is accomplished by regulating the screw 17, it is possible to readily re-adjust the spark gap whenever required. The oscillator connected as here shown, may be used for radio telephone work, if desired, by opening switch 12 and closing a switch 12^a, which serves the function of bridging key 33, or the station may be employed for radio telegraph work by closing the switch 12 and opening the switch 12^a, it being understood, 110 however, that the main switch 2 in the direct current circuit, must first be closed when it is desired to operate the station.

The change from telephone to telegraphic service is practically instantaneous as it is 115 only necessary to operate the switches 12 and 12^a to change the current flow through the different instruments employed.

While the structure here shown is more or less specific, I wish it understood that 120 various changes in form, proportions and minor details of construction may be resorted to within the scope of the appended claims; similarly, that the materials and 125 finish of the several parts employed may 130

be such as the experience and judgment of the manufacturer may dictate.

Having thus described my invention, what I claim and desire to secure by Letters Patent is—

- 5 1. In an oscillator, a pair of electrodes, means for circulating a liquid through and between the electrodes, means for contacting and separating the electrodes, and means 10 cooperating with said last mentioned means for stopping the circulation of liquid through the electrodes when they contact, and for re-establishing the circulation when the electrodes are separated.
- 15 2. An oscillator comprising a pair of tubular electrodes, a stationary hollow base member supporting one of said electrodes, a movable rod supporting the other electrode, a container enclosing the electrodes, 20 said container being filled with distilled water to maintain the electrodes in a submerged condition, a supply tank for distilled water, a pipe connecting said tank with the hollow base supporting the first-named tubular electrode, an overflow pipe connected 25 with the container enclosing the electrodes, said pipe being connected with the suction side of a circulating pump, a pipe connecting the discharge end of the pump with the 30 supply tank, a valve controlling the flow of water from the supply tank to the hollow base member, a magnet adapted to open and close said valve, a second magnet adapted to lift the movable electrode, and means for

simultaneously making or breaking a circuit 35 through said magnets.

3. In an oscillator a pair of electrodes, a container enclosing the same, said container containing a non-electrolytic liquid maintaining the electrodes in submerged condition, means for contacting and separating the electrodes, means for circulating the liquid between the electrodes, and means for automatically stopping the circulation of the liquid between the electrodes when they 45 contact, and for automatically re-establishing the circulation when the electrodes are separated.

4. In an oscillator of the character described a container, distilled water in said 50 container and a pair of electrodes submerged therein, said electrodes being constructed of tungsten metal.

5. In an oscillator of the character described a container, distilled water in said 55 container, a pair of electrodes submerged therein, said electrodes being tubular in formation and constructed of tungsten metal and means for maintaining a circulation of water through and between the 60 electrodes.

In testimony whereof I have hereunto set my hand in the presence of two subscribing witnesses.

ALPHONSUS L. GOLDEN.
